(57) **CLAIM**

The ornamental design for a sunglass, as shown and described.

DESCRIPTION

FIG. 1 is a front top perspective view of the sunglass of the present invention showing my new design;
 FIG. 2 is a front elevational view thereof;
 FIG. 3 is a rear elevational view thereof;
 FIG. 4 is a left side elevational view thereof;
 FIG. 5 is a top plan view thereof; and,
 FIG. 6 is a bottom plan view thereof.
